Primary Examiner—Louis S. Zarfas*Assistant Examiner*—Monica A. Weingart*Attorney, Agent, or Firm*—Patterson, Belknap, Webb & Tyler LLP**[57] CLAIM**

The ornamental design for building element for a canopy fascia, as shown.

DESCRIPTION

FIG. 1 is a perspective view of a building element for a canopy fascia showing my new design;
FIG. 2 is a top view of my design;
FIG. 3 is a side view of my design; and,
FIG. 4 is a front view of my design.

The broken line showing of the extended arm of the fascia is for illustrative purposes only and forms no part of the claimed design.
